UNITED STATES PATENT OFFICE.

CHARLES WAGNER, OF BROOKLYN, NEW YORK, ASSIGNOR TO THE BRYANT ELECTRIC COMPANY, OF BRIDGEPORT, CONNECTICUT, A CORPORATION OF CONNECTICUT.

ELECTRIC FITTING.

1,156,727.

Specification of Letters Patent.

Patented Oct. 12, 1915.

Application filed July 9, 1913. Serial No. 778,098.

To all whom it may concern:

Be it known that I, CHARLES WAGNER, a citizen of the United States of America, and residing at Brooklyn, in the county of Kings and State of New York, have invented a certain new and Improved Electric Fitting, of which the following is a specification.

My invention relates to electric fittings and particularly to candelabrum sockets, the 10 object of my invention being to provide a device of this character having certain improved features of construction hereafter pointed out and illustrated in the accompanying drawing in which,

15 Figure 1 is a broken elevation of a construction in which my invention is embodied in one form; Fig. 2 is a side elevation of the body of the switch; Fig. 3 is a perspective of certain details; Fig. 4 is a side elevation of 20 a portion of the switch casing; Fig. 5 is a side elevation of a modified form with portion of the casing dropped and in perspective; and Fig. 6 is a side elevation of a further modification.

25 In the form shown in Figs. 1 to 4, the present fitting comprises a switch arranged within a two-part casing 10, and 11, the uniting ends of which are sleeved together and detachably connected. The latching 30 elements 12 and 13 may be of any suitable type, and are here shown in a preferred construction in which the latching elements 12 on one of the parts are many times repeated so that the casing may be readily assembled

35 in substantially any relative rotary position of the parts. To facilitate unlatching, the inner sleeving end of the casing is slotted at 14 so that it may be pressed in, thus freeing the adjacent latching elements and permitting 40 the parts to be rocked apart. At opposite ends of the casing, each part 10 and 11 carries a threaded metallic bushing 15 into which are threaded the ends of the wire conduits 16 and 17 respectively. A candelabrum socket 18 is carried at the upper 45 end of conduit 17 to receive the miniature lamp 19.

Within the casing, a switch body is arranged, here comprising a pair of insulating 50 buttons 20, 21, spaced apart to receive a switch mechanism and grooved in register in their peripheries at 22, 23 to permit the free passage of the leading-in wire 24 past the switch to one of the socket terminals 26.

55 The other leading-in wire 25 is secured to

the wire terminal 27 on the switch body. From the second wire terminal 28 a connecting wire 29 leads to the second binding screw (not shown) on the lamp socket 18.

Between the two wire terminals on the 60 switch body, any suitable switch mechanism is arranged. That here shown is of the well known ratchet actuated type in which stationary contacts (not shown) respectively connected to the wire terminals 27 and 28 65 are engaged by the winged contact piece 30 which rides over a ratchet formed boss 31 and to which rotary motion is imparted by the ratchet 32. The latter is carried by a plate 33 of insulating material, at the outer 70 end of the arm 34 of which is a downwardly extending tongue 35 into which a pin 36 is screwed. Surrounding the casing and normally confined between the rim of the casing element 10 and a bead 37 on the element 75 11, is a milled actuating ring 38 perforated at 39 to engage the pin 36, the inner end of which is passed therethrough and through the slot 40 and screwed into the tongue 35 after the parts have been assembled. Upon 80 rotation of the ring 38 in one direction, the ratchet 32 is operated to move the switch piece into the "on" or "off" position of the switch as the case may be. Upon release of the ring, the latter is returned to position 85 by the switch spring 41, the oscillation of the ring in both directions being limited by the extent of slot 40 in the casing element 11 in which the pin 36 engages.

As is usual in candelabrum sockets, the 90 wire conduit 17 is surrounded by a candelabrum tube 42 of opaque glass, at the bottom of which is arranged the dished plaque 43 in imitation of a drip plate. In order to afford suitable seats for the bases of these 95 parts, the casing element 10 may be shouldered as at 44. In Fig. 5, stepped seats of this character are dispensed with, the drip plate resting directly on the shoulder formed between the body and nipple of the casing, 100 while the tube 42 rests on the plate 43. In this figure, I have shown the switch operated by a pull chain 45 passing out through the chain bell 46 and connected to the ratchet plate 33 in well understood manner. 105

In Fig. 6, I have shown a key 47 for a switch of another type arranged within a casing in which certain features of my invention are embodied.

Various other modifications and variations 110

of my invention will readily suggest themselves and the constructions shown are to be regarded as merely illustrative of my invention.

5 I claim as my invention:—

1. An electric fitting of the type described, comprising a switch, an insulating body on which the same is mounted, a casing inclosing the switch, wire conduits secured at opposite ends of the casing for leading wires to and from the switch, and a candelabrum seated on one end of said casing, substantially as described.

10 2. An electric fitting of the type described, comprising a switch, an insulating body on which the same is mounted, a two-part casing sleeved together and provided with co-operating readily detachable latching elements, and wire conduits secured at opposite ends of the casing for leading wires to and from the switch, and a candelabrum supported on one end of the casing.

15 3. An electric fitting of the type described, comprising a switch, an insulating body on which the same is mounted, a casing inclosing the same, a ratchet for operating the switch, a ring surrounding said casing and an operative connection between said ring

and the ratchet whereby said switch may be actuated together with wire conduits secured to opposite ends of the casing for leading wires to and from the switch, and a candelabrum seated on one end of said casing and surrounding the conduit attached thereto, substantially as described.

30 4. An electric fitting of the type described, comprising a switch, an insulating body on which the same is mounted, a casing inclosing the same, and circumferentially slotted, a ratchet for operating the switch and a member moving therewith projecting through said slot in the casing to afford an operative connection for actuating the switch together with wire conduits secured to opposite ends of the casing for leading wires to and from the switch, and a candelabrum seated on one end of said casing and surrounding the conduit attached thereto, substantially as described.

35 45 In testimony whereof I have signed my name to this specification, in the presence of two subscribing witnesses.

CHARLES WAGNER.
